(57) CLAIM

The ornamental design for a toy head with ribbon on cheek, as shown and described.

DESCRIPTION

FIG. 1 is a front view of a toy head with ribbon on cheek according to my new design;

FIG. 2 is a rear view thereof;

FIG. 3 is a right side view thereof;

FIG. 4 is a left side view thereof; and,

FIG. 5 is a top view thereof.

The broken line showing of the body is for illustrative purposes only, and forms no part of the claimed design.
